Corbie Wilcox

By Watson E. Coleman

Attorney

UNITED STATES PATENT OFFICE.

CORBIE WILCOX, OF MART, TEXAS.

TRAP.

Application filed November 11, 1924. Serial No. 749,244.

To all whom it may concern:

Be it known that I, CORBIE WILCOX, a citizen of the United States, residing at Mart, in the county of McLennan and State 5 of Texas, have invented certain new and useful Improvements in Traps, of which the following is a specification, reference being had to the accompanying drawings.

This invention relates to certain improvements in traps and it is an object of the invention to provide a novel and improved device of this general character including a rotatable platform together with means for rotating the platform upon movement of a 15 trigger by the victim.

Another object of the invention is to provide a novel and improved device of this general character employing a rotating platform together with means whereby said 20 platform is automatically reset.

The invention consists in the details of construction and in the combination and arrangement of the several parts of my improved trap whereby certain important advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:

Figure 1 is a view in side elevation illustrating a trap constructed in accordance 35 with an embodiment of my invention;

Figure 2 is a fragmentary view in elevation illustrating certain parts in a second 40 position;

Figure 3 is a fragmentary elevational view illustrating certain parts in a third position particularly during a reset of the platform;

Figure 4 is a fragmentary view in perspective of the outer end portion of the operating rock arm for controlling the operation of the platform;

Figure 5 is a view in top plan of the structure as illustrated in Figure 1;

Figure 6 is a sectional view taken substantially on the line 6—6 of Figure 5.

As disclosed in the accompanying drawings. H denotes a housing of requisite di-

mensions and which has its top at one end 55 portion disposed on a downward and outward incline to provide a runway 1 whereby the victim may readily climb upon the top wall 2 of the housing.

The top wall 2 at a point in relatively 60 close proximity to the runway 1 is provided with an opening 3 extending substantially entirely across the top wall 2 and which opening is adapted to be normally closed by the rotating platform 4.

The central portion of the platform 4 is 65 fixed to a shaft 5 extending transversely across the top wall 2 of the housing H and having each end portion rotatably supported by an upstanding bearing 6 herein disclosed 70 as secured to a side wall 7 of this housing H.

The shaft 5 extends beyond opposite sides of the housing H and fixed to one extended end portion of the shaft 5 is the gear 8 meshing with a gear 9 fixed to a driving 75 shaft 10. This shaft 10 is mounted upon and disposed transversely of the top wall 2 of the housing H and is rotatably supported by the bearings 11. The shaft 10 together with the gear 9 is adapted to be rotated in 80 the direction indicated by the arrow a by the clock spring 12, such rotation of the shaft 10 and gear 9 operating to rotate the gear 8 and the shaft 5 in the direction indicated by the arrow b.

The opposite extended portion of the 85 shaft 5 has fixed thereto a depending rock arm 14. The free end portion of this lever 14 is provided with an outstanding member 15 which is engaged through an elongated 90 slot 16 provided in the holding lever 17. One end portion of the lever 17 being pivotally connected, as at 18, for vertical swinging movement to the adjacent side wall 7 of the housing H. The slot 16 is of a length to 95 permit a complete rotation of the shaft 5 without hindrance or obstruction being offered to such rotation by the rock arm 14.

The free end portion of the lever 17 is 100 provided with an upstanding bill 19 disposed on desired incline with respect to the lever 17 and with which is adapted to engage the bill 20 of the upstanding hook member 21 pivotally connected, as at 22, to the side wall 7 just referred to. With the 105 bill 20 of the hook member 21 in engagement with the bill 19 of the lever 17, the lever 17 through the medium of the rock

arm 14 holds the shaft 5 and the gear 8 against rotation with the platform 4 in a position to substantially close the opening 3 and also in a position substantially co-planar with the top wall 2 of the housing H.

The pivoted end portion of the hook member 21 is provided with an angularly disposed arm 23 extending beyond the adjacent end of the housing H. Fixed to the outer or free end portion of the arm 23 is a flexible member 24 which extends down inwardly and disposed through the guide openings 25 provided in the outstanding fixed arm 26 carried by the housing H. The flexible member 24 extends upwardly of the adjacent end of the housing H and through the suitable guides 27 over the top wall 2 and secured to an end portion of a trigger 28. This trigger 28 is supported substantially intermediate its ends for vertical swinging movement by an upstanding bearing post 29 mounted upon the top wall 4. The opposite end portion of the trigger 28 partially overlies the opening 3 and said end portion has tied or otherwise secured thereto the bait 30.

As the victim passes up the runway 1 to reach the bait 30 such victim will be positioned upon the platform 4 and as the victim exerts pull upon the bait 30 the outer end of the trigger 28 will be swung upwardly resulting in sufficient pull upon the flexible member 24 to swing the bill 20 of the hook member 21 out of engagement with the bill 19 of the lever 17, whereupon the spring 12 will function to cause the meshing gears 9 and 8 to rotate the shaft 5 together with the platform 4, resulting in the victim being cast within the housing H.

The shaft 5 outwardly of the gear 8 is provided with a second rock arm 31 which, when the shaft 5 has made substantially a three quarters turn contact from above with a shoe 32 pivotally connected, as at 33, with the outer end portion of a rock arm 34. This rock arm 34 is fixed to an extremity of a shaft 35 extending across an end wall of the housing H adjacent to the arm 26 and at a point between said arm 26 and the arm 23. The opposite end portion of the shaft 35 has fixed thereto the disc 36 having the straight edge 37 which is substantially horizontally disposed when the platform 4 is in its normal or closed position. When the hook member 21 is disengaged from the lever 17 the arm 23 comes in contact with said straight edge 37 as is particularly illustrated in Figure 2 of the accompanying drawings. When the arm 31 comes into contact with the shoe 32, the continued movement of the arm 31 will swing the arm 34 downwardly resulting in a rotation of the shaft 35 and the disc 36, said rotation being inwardly and downwardly resulting in the straight edge 37 moving inwardly to-

ward the housing H and constituting a cam to raise the arm 23 upwardly and consequently swing the hook member 21 inwardly to bring the bill 20 in the path of travel of the bill 19 so that as the arm 17 is swung upwardly by the rock arm 14, the platform 4 will be held against further rotation when said platform is returned to its horizontal or closing position as illustrated in Figure 6.

The shaft 35 is rotatably supported by the upstanding bearings 39 secured to the side walls of the housing H and fixed to said shaft 35 in one of said bearings 39 is a wheel 40. Secured to the periphery of the wheel and depending therefrom is a flexible member 41 to which is secured a member 42 of desired weight. This weight 42 serves to normally maintain the disc 36 in its position particularly illustrated in Figures 1 and 2, said weighted member 42 functions to return the disc 36 to such position when the arm 31 passes down free of the shoe 32.

Through the medium of the disc 36 and the arms 31 and 34, the platform 4 is automatically reset so that after a capture, the trap is in proper adjustment for another victim.

Arranged within the housing H adjacent one end thereof is a block or head 43 provided at its central portion with an upstanding stem or plunger 44 which is disposed through the top wall 2 of the housing. This head or block 43 is employed to kill a victim received within the housing H, it being understood that the victim is caused to be positioned between the bottom wall of the housing and the block or head 43 wherein upon requisite pressure being imposed upon the stem or plunger 44 the victim will be crushed to death. In order to remove the victim a side wall 7 of the housing H is provided with a normally closed door 45.

When it is desired to rewind the spring 12 the shoe 32 is swung to a position to be out of the path of travel of the arm 31 whereby said arm 31 may be readily rotated in a direction to wind said spring.

From the foregoing description it is thought to be obvious that a trap constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A trap comprising, in combination a housing having an opening in its top wall,

a rotatable platform for closing said opening, power means for rotating said platform, an arm rotating with the platform, a pivoted lever, said lever being operatively

5 engaged with the arm, means engaging the lever to hold the arm and platform against rotation when the platform is in closed position, a bait trigger, and means operating upon movement of the trigger for releasing

10 the holding means from the lever.

2. A trap comprising, in combination a housing having an opening in its top wall, a rotatable platform for closing said opening, power means for rotating said platform, an arm rotating with the platform, a pivoted lever, said lever being operatively engaged with the arm, means engaging the lever to hold the arm and platform against rotation when the platform is in closed position, a bait trigger, means operating upon movement of the trigger for releasing the holding means from the lever, and means operating as the platform rotates for resetting said holding means.

25 3. A trap provided with a housing with an opening in its top, a shaft disposed across said opening in the housing, a platform carried by the shaft and rotating therewith, said platform when in one position closing 30 said opening, driving means for rotating the shaft and platform, an outstanding arm carried by the shaft, a lever pivotally supported by the housing, said arm and lever being operatively connected, a swinging 35 hook member carried by the housing and engaging the lever to hold the platform in closed position, a bait trigger, and an operative connection between the bait trigger and the hook member for disengaging the 40 hook member from the lever upon movement of the bait trigger.

4. A trap provided with a housing with an opening in its top, a shaft disposed across said opening in the housing, a platform carried by the shaft and rotating therewith, said platform when in one posi-

tion closing said opening, driving means for rotating the shaft and platform, an outstanding arm carried by the shaft, a lever pivotally supported by the housing, said 50 arm and lever being operatively connected, a swinging hook member carried by the housing and engaging the lever to hold the platform in closed position, a bait trigger, an operative connection between the bait 55 trigger and the hook member for disengaging the hook member from the lever upon movement of the bait trigger, and means operated from the shaft for returning the hook member in position to engage the lever 60 to hold the platform in closed position.

5. A trap provided with a housing with an opening in its top, a shaft disposed across said opening in the housing, a platform carried by the shaft and rotating therewith, said platform when in one position closing 65 said opening, driving means for rotating the shaft and platform, an outstanding arm carried by the shaft, a lever pivotally supported by the housing, said arm and lever 70 being operatively connected, a swinging hook member carried by the housing and engaging the lever to hold the platform in closed position, a bait trigger, an operative connection between the bait trigger and the 75 hook member for disengaging the hook member from the lever upon movement of the bait trigger, an outstanding arm carried by the hook member, a shaft, a cam member carried by the shaft and with which 80 the arm of the hook member engages when said hook member is in released position, and coacting means carried by both of the shafts for rocking the second shaft in a direction during the rotation of the first named 85 shaft to cause the cam to move the arm of the hook member in a direction to return the hook member to a position to again engage the lever.

In testimony whereof I hereunto affix my 90 signature.

CORBIE WILCOX.
